CLAIM

The ornamental design for a document scanner as shown and
described.

DESCRIPTION

FIG. 1 is a perspective view of the document scanner.

FIG. 2 is a front elevation view thereof.

FIG. 3 is a rear view thereof.

FIG. 4 is a bottom view thereof.

FIG. 5 is a top view thereof.

FIG. 6 is an end view thereof; and,

FIG. 7 is the other end view thereof.

The features shown in broken lines depict environmental
subject matter only and form no part of the claimed design.
